(57) **CLAIM**

The ornamental design for a step, as shown and described.

DESCRIPTION

FIG. 1 is a front, left side, top perspective view of a first embodiment of a step showing our new design;

FIG. 2 is a rear, left side, top perspective view thereof;

FIG. 3 is a front view thereof;

FIG. 4 is a rear side view thereof;

FIG. 5 is a left side view thereof shown in enlarge scale relative to FIG. 1;

FIG. 6 is a right side view thereof;

FIG. 7 is a top view thereof shown in the scale of FIG. 1;

FIG. 8 is a bottom view thereof;

FIG. 9 is a front, left side, top perspective view of a second embodiment of the step;

FIG. 10 is a rear, left side, top perspective view thereof;

FIG. 11 is a front view thereof;

FIG. 12 is a rear side view thereof;

FIG. 13 is a left side view thereof shown in enlarge scale relative to FIG. 9;

FIG. 14 is a right side view thereof;

FIG. 15 is a top view thereof; and,

FIG. 16 is a bottom view thereof shown in the scale of FIG. 9.
